United States Patent Office

Des. 181,445
Patented Nov. 12, 1957

181,445

APPAREL BELT

William Sauer, Teaneck, N. J., assignor to Annette Belts,
Inc., New York, N. Y., a corporation of New York

Application August 28, 1956, Serial No. 42,762

Term of patent 3½ years

(Cl. D3—10)

Fig. 2.

Fig. 1.

Fig. 3.

Fig. 4.

Fig. 1 is a front view of an apparel belt, showing my new design.

Fig. 2 is a top plan view thereof.

Fig. 3 is a fragmentary rear view thereof, with part broken away, to disclose the inner surface of the front wall thereof.

Fig. 4 is a view similar to Fig. 1, showing the belt as it appears with the securing straps in an alternative position of adjustment.

I claim:

The ornamental design for an apparel belt, substantially as shown.
